LESLIE A. RAWSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

DETACHABLE LADDER AND CAGE CONSTRUCTION

Application filed February 12, 1929. Serial No. 339,308.

My invention relates to ladder and cage construction for derricks, and one of the advantages of the invention resides in the provision of ladder and cage structure adapted for detachable connection to any type of derrick.

Another object of the invention is to provide for the complete elimination of bolts and nuts passing through the derrick legs or the reinforcing braces and substituting therefor detachable clamping means for connecting the ladder and cage to the derrick structure.

In the operation of drilling a well it is necessary to employ a relatively high derrick, and on the top of the derrick in the ordinary manner is located the crown block and other apparatus for installing and pulling the well string. In modern oil field practice the derricks are of the fabricated type and may be assembled or dismantled at the well. It is frequently necessary for workmen to go to the top of the derrick for repairs to the pulleys on the crown block, and ordinarily iron ladders are riveted to the derrick structure. This procedure involves the erection of ladders for every derrick, and likewise when the derrick is dismantled the ladders are detached from the derrick structure, which involves quite an expense and extra work.

In the present invention the ladder and cage may be connected to the ordinary and well known types of derricks and be quickly detached therefrom for use in connection with other derricks.

A further object of the invention is to provide a ladder and cage structure of sectional or knock-down type which is adapted for detachable connection to all derricks now in use.

The invention to be specifically described hereinafter is adaptable for use with any derrick structures, but is especially designed for use in connection with derricks in the oil fields, though of course it may be readily used in connection with oil or gas storage tanks in a similar capacity.

I will now describe the structure which entirely eliminates the above and other disadvantages, reference being had to the accompanying drawings in which:

Fig. 1 is a partial side elevational view of

a pumping or a drilling derrick provided with my improved ladder and cage construction.

Fig. 2 is a perspective view of my improved ladder and cage construction illustrating partially its assembly.

Fig. 3 is a sectional view taken on line 3—3 of Fig. 2 showing the attachment of the cage to the derrick structure and with a portion of the latter in elevation.

Fig. 4 is a sectional view taken on line 4—4 of Fig. 2, and showing the connecting means for the ladder to a supporting bar.

Fig. 5 is a vertical sectional view taken through the cage supporting bars and illustrating one of the bolts for connecting the cage to the derrick structure.

Referring to the drawings more in detail 10 indicates the legs of any ordinary derrick, the legs being formed in sections, as 70 usual, and connected in any desired manner, as by rivets. The means I have shown for bracing the legs comprises diagonal braces 12, girt bars 13, and gussets 14, which latter connect the braces 12 and girt bars 13 to the 75 derrick legs 10.

The base support and anchoring means for the derrick constitute no particular part of the present invention, and in Fig. 1 I have therefore merely indicated the conventional 80 form of mounting, comprising the concrete pedestals 15 and 16 for the derrick and concrete pedestals 17 and 18 supporting the end housings 19 and 20.

It may be understood that the body of the 85 derrick structure may be of any desired type or construction, and as the particular construction thereof forms no part of the present invention, the above description will be sufficient.

One of the radical changes in ladder and cage construction included in the subject matter of the present invention is the manner of mounting the ladder and cage to the side structure of the derrick. In prior derrick 90 constructions the ladder and its associated cage structures have been fixed to the derrick body, so that they are immovable with respect to the body without dismantling the derrick, or they may be removed from the 95 100

derrick structure by burning out the holding rivets or removing bolts provided for that purpose. In the present construction the ladder and cage constructions are detachably mounted on the derrick structure and may be readily removed and attached to other derricks.

The invention is not, of course, limited to the specific means for accomplishing the detachable connection between the ladder and cage constructions and the derrick body; but, on the contrary, the invention relates broadly to a ladder and cage construction detachable with respect to the body, and it is to be understood that the invention includes any and all means by which this may be accomplished.

The ladder construction is indicated generally by the numeral 21, while the cage construction is indicated by the numeral 22. The ladder construction comprises a series of ladder sections 23 of conventional form used in connection with steel derricks but which in the past have been fixedly connected by horizontal supports to the derrick frame. Each ladder section 23 comprises side rails 24 and 25 which are connected together in the usual manner by rounds 26. The number of the ladder sections and their associated cages employed, of course, depends entirely upon the height of the derrick to which they are to be attached, and likewise upon the number of rest and safety stops indicated by the cages numbered generally as 22. The ladder sections 23 and cages 22 being each of similar construction, only one unit comprising a ladder and a cage will be described.

Each ladder section 23 has connected to its side rails 24 and 25 by rivets 27, as illustrated in Fig. 4, the angle bars 28 and 29 which have their inner ends resting upon the upper horizontal leg of angle girts 30 which may form one of the horizontal bars of the derrick, or which may be connected by bolts or rivets to the derrick legs 10.

The girts 30 are welded or bolted to the legs 10 of the derrick at intervals, though they are more particularly adapted for position between the cage systems 22. Extending downward through suitable openings in the angle bars 28 and 29 adjacent to the vertical leg 31 of an angle girt 30 are the hook bolts 32. Heads 33 of the hook bolts 32 are adapted to hook around a vertical leg 34 of the angle girt 30 and clamp the parts together when nuts 35 on threaded upper ends 36 of said bolts 32 are tightened against the angle bars 28 and 29. Connected to the derrick legs 10 and arranged in spaced relation throughout the height of the derrick are angle girts 37 of identical construction to that of the intermediate angle girts 30. The angle girts 37 are arranged in pairs and are connected by rivets or bolts to the derrick legs 10, being adapted for supporting the

cage construction 22 in a manner as will now be described.

The cage construction 22 comprises horizontal angle rails 38 and 39, the inner ends of which are adapted to rest upon the horizontal legs of the lower angle girt 37, which likewise may form one of the horizontal bars of the derrick. The outer ends of the rails 38 and 39 are riveted to upwardly and inwardly inclined angle bars 40 and 41. The upper parts of the angle bars 40 and 41 are bent over at obtuse angles to dispose the ends 42 thereof in horizontal planes, and the ends 42 are adapted to rest upon the horizontal leg of an angle girt 37 disposed above the other girt. A frame 43 is adapted for connection by bolts or rivets to the angle rails 38 and 39 and angle bars 40 and 41 in the following manner.

The cage frame 43 comprises upright angle bars 44 and 45 connected at their lower ends to the outer ends of the rails 38 and 39, while the upper ends of the bars 44 and 45 are connected to the angle bars 40 and 41 by bars 46 and 47. Cross-bars 48, 49, and 50 connect the upright bars 44 and 45 and provide a semi-enclosed landing at this point.

As heretofore stated the inner ends of the rails 38 and 39 rest upon the lower angle girt 37, and for holding the same in position thereon I provide bolt hooks 51 clearly illustrated in Fig. 5. These hook bolts 51 extend downward from the rails 38 and 39 and have heads 52 which hook around a vertical leg 53 of the angle girt 37, nuts 54 being screwed upon threaded ends 55 of said hook bolts 51, and when tightened serve to draw the hook portions or heads 52 around the vertical leg 53 of the angle girt 37.

The upper bent over ends 42 of the angle bars 40 and 41 which rest upon the upper angle girt 37 carry hook bolts 56 and 57 of identically the same construction as the bolts 32 and 51 and are attached to the upper angle girt 37 in the manner described.

The ladder sections 21 are offset from each other in vertical plane and are connected to the derrick frame in such manner that the upper and lower ends within the respective cage structures 22 are arranged side by side. The cage structures as described provide transfer platforms for the workmen climbing the derrick, that is to say, the workmen transfer at these points from ladder to ladder. The cage structures serve likewise to catch a person who might fall from one of the higher ladder sections.

The ladder and cage sections thus described may be readily dismantled from the derrick by simply unscrewing the nuts 35 and 54, to provide for the removal of the hook bolts 32, 51, and 57.

What I claim and desire to secure by Letters Patent is:

1. The combination with a derrick having

a frame and angle girts of: ladder sections, cage sections surrounding the ends of said ladder sections; bars connected to said ladder sections and engaging said angle girts; bars connected to said cage sections and engaging said girts; and hook bolts carried by said bars and adapted for engagement with said girts for detachably supporting said sections upon said derrick frame.

10 2. The combination with a derrick having a frame and transverse girts of: a series of ladder sections; cage sections surrounding the ends of said ladder sections; angle bars secured to said ladder and cage sections and being supported upon said girts; and hooks secured to said angle bars and adapted to be hooked around said girts for detachably clamping said ladder and cage sections upon said derrick frame.

15 3. The combination with a derrick including reinforcing girts of: a series of ladder and cage sections adapted for attachment to said derrick, said cage sections surrounding the ends of said ladder sections to provide transfer points from one ladder section to another; and hook members carried by said ladder and cage sections for detachably connecting said sections to said girts.

20 4. The combination with a derrick having a frame including reinforcing girts of: a ladder section; a cage section surrounding an end of said ladder section to provide a transfer platform therefor; and hook bolts carried by said ladder and cage sections adapted for detachable connection to said girts.

25 5. The combination with a derrick having a frame including girts of: a ladder; bars secured to said ladder and being supported upon girts; and hook bolts carried by said bars and adapted for engagement with said girts for detachably supporting said ladder on said derrick frame.

30 6. The combination with a derrick frame including transverse girts of: a series of ladder sections adapted for attachment to said derrick; bars secured to said ladder sections and being supported upon said girts; and hook elements carried by said bars and engaging said girts for detachably clamping said ladder sections upon said derrick frame.

35 7. The combination with a derrick frame including angle girts of: a ladder; bars secured at one end to said ladder and having their opposite ends supported on said girts; and hook members connected to the free ends of said bars and adapted to be hooked around said girts for detachably supporting said ladder upon said derrick frame.

40 8. The combination with a derrick frame including girts of: a ladder; angle bars secured to said ladder and being supported upon said girts; and hooks secured to said angle bars and adapted to be hooked around said girts for detachably supporting said ladder thereon.

In testimony whereof, I have hereunto set my hand at Los Angeles, California, this 4 day of February, 1929.
